UNITED STATES PATENT OFFICE

116,867

DESIGN FOR A CUP HOOK

Jacob Strand, New York, N. Y.

Application February 10, 1939, Serial No. 82,905

Term of patent 14 years

To all whom it may concern:

Be it known that I, Jacob Strand, a citizen of the United States, residing in the Borough of Manhattan, city, county, and State of New York, have invented a new, original, and ornamental Design for a Cup Hook, of which the following is a specification, reference being had to the accompanying drawing, forming a part thereof.

In the drawing—

Fig. 2 is a front elevation thereof; and

Fig. 3 is a partial section on the line 3—3, Fig. 2.

I claim

The ornamental design for a cup hook, substantially as shown.

JACOB STRAND.
